UNITED STATES PATENT OFFICE.

HAROLD GRAY, OF LOMBARD, ILLINOIS.

DESIGN FOR A DOLL.

Application filed May 21, 1925. Serial No. 13,530. Term of patent 14 years.

To all whom it may concern:

Be it known that I, HAROLD GRAY, a citizen of the United States, residing at Lombard, in the county of Du Page and State of Illinois, have invented a new, original, and ornamental Design for Doll, of which the following is a specification, reference being had to the accompanying drawing, forming part thereof.

The figure is a perspective view of a doll embodying my new design.

I claim:

The ornamental design for a doll as shown.

HAROLD GRAY.
